Edward W. Strong, Stony Brook, N. Y., assignor
to Gyrodyne Company of America, Inc., Flower-
field, N. Y., a corporation of New York

Application April 29, 1952, Serial No. 19,513

Term of patent 14 years

(Cl. D71—1)

To all whom it may concern:

Be it known that I, Edward W. Strong, a citizen of the United States of America, residing at Stony Brook, in the county of Suffolk and State of New York, have invented a new, original, and ornamental Design for a Rotary Wing Aircraft, of which the following is a specification, reference being had to the accompanying drawing, forming part thereof.

In said drawing:

Fig. 1 is a perspective view of a rotary wing aircraft, showing my new design, with the landing gear retracted.

Fig. 2 is a perspective view of the same seen from the opposite side, with the landing gear down.

Fig. 3 is a plan of the same.

Fig. 4 is a side elevation of the same.

Fig. 5 is a front elevation of the same.

I claim:

The ornamental design for a rotary wing aircraft, as shown.

EDWARD W. STRONG.
